UNITED STATES PATENT OFFICE.

JOHN DENTON, OF PATERSON, NEW JERSEY.

FLUSHING APPARATUS.

1,109,971.

Specification of Letters Patent. Patented Sept. 8, 1914.

Application filed March 6, 1913. Serial No. 752,323.

To all whom it may concern:

Be it known that I, JOHN DENTON, a citizen of the United States, residing at Paterson, in the county of Passaic and State of New Jersey, have invented certain new and useful Improvements in Flushing Apparatus, of which the following is a specification.

This invention relates to flushing apparatus of that type in which means is employed for mechanically lifting the body of water in the short leg of a siphon up over the bend and into the long leg of the siphon for the purpose of starting the siphoning action.

It is desired that the operating handle or lever in such apparatus shall have little throw or range of movement but that the means for transmitting the motion therefrom to the siphon starting means shall be such that the latter may have a throw sufficient always to insure starting of the siphon.

One object of the invention is therefore to provide a transmitting lever system which will impart the desired throw and yet be compact, *i. e.*, not only with respect to its over-all length, whereby to be adapted to the smallest tanks, and its over-all thickness, whereby to afford clearance for reaching down into the tank for access to the apparatus in assembling or effecting repairs, but with respect to its over-all dimension when extended.

Another object is to improve the water-lifting means with a view to obtain a complete or exhaustive discharge of the water from the short leg of the siphon, while permitting the prompt reestablishment of the water in the short leg of the siphon upon the parts assuming their rest positions.

Another object is so to construct the siphon as to make unnecessary the packing of the opening therein through which the lifting means projects so as to cut off the inrush of air during the siphoning action.

In the accompanying drawing, Figure 1 is a side elevation, partly broken away, of the improved flushing apparatus; Fig. 2 is a fragmentary view illustrating the transmission means whereby the operating handle or the like is connected with the lifting means and also showing in section that part of the siphon through which the lifting means projects; Fig. 3 is a vertical sectional view on the line $x-x$ of Fig. 2; Fig. 4 is a vertical sectional view on the line $y-y$ of Fig. 5 (and partly broken away) of the lifting means and the short leg of the siphon; and,

Fig. 5 is a horizontal sectional view through the short leg of the siphon in a plane above the lifting means.

As in my Patents Nos. 768215 and 833681 the siphon includes with the long leg a , penetrating and suitably secured in the bottom wall of the tank b , a short leg c which is appreciably greater in diameter than the leg a and in the present instance consists of a cylinder which is screwed into the neck or bend-member d of the siphon, in turn screwed upon the upper end of the leg a . The part of the member d into which the cylinder c is screwed is a relatively offset portion d' of member d forming a top wall or cap for the cylinder c of such form that the longitudinal axis of the cylinder passes through the cap exteriorly of the body part of the member d .

Axially of the cylinder there is screwed into the threaded hole e formed in the cap d' a downwardly depending tube f . Through this tube extends the stem g of the lifting means also including a piston h attached to the lower end of the stem and to be described in detail. i is a handle (in this case a short lever fulcrumed in a bracket j attached to the tank) for imparting the upward or starting stroke to the water-lifting means. For transmitting the motion from the handle i to the lifting means in a manner calculated to produce a material amplification of the movement effected I employ the following mechanism:

A triangular bracket k is secured flat against the inside of one of the walls of the tank and has an overhang l resting upon and suitably secured to said wall. On a stud m in the bracket is fulcrumed between its ends a lever n . The long arm n' of this lever, which is connected with the handle i by the link o , stands normally approximately horizontal and is joined with the short arm n'' of the lever by the vertical portion n^3 ; the arm n'' also extends substantially horizontally, and it is formed at its extremity with the teeth n^4 . The lever n is arranged in a vertical plane close to the inner face of the bracket k and hence to one vertical wall of the tank (Fig. 3).

p is a lever arranged side by side with and close to lever n and fulcrumed on a stud q in bracket k horizontally aligned with the stud m . On the side of lever p adjoining lever n it has a boss formed with the peripheral teeth r , the same meshing with the teeth n^4 .

of lever n . (I cast the lever p with an opening s opposite the toothed portion of the boss so as to admit a file or other tool for finishing off the teeth of the boss.) The free end of the lever has a longitudinal slot t receiving the bent-off upper end g' of the stem g , which has a nut g^2 to retain said end in the slot.

In view of the foregoing it will be apparent that although the handle i is allowed but comparatively little movement, still the motion transmitted thereby through the lever system is sufficiently amplified so that a quick and considerable movement of the lifting means will occur. In the rest position of the lever p it stands downwardly inclined from its fulcrum, and as the angular lever n has its part n' elevated and its part n^2 depressed, part n^2 can rise without projecting above the top of the tank, and part n' can descend without interfering with the bent-off end g' of stem g , to an extent perfectly ample for insuring the needed extent of movement to the lifting means g .

The piston h is constructed as follows: u is a disk which is fixed on the lower reduced end of the stem g by the nut v and has on both sides of the diametrical rib w the relatively large openings x . In the pairs of upstanding lugs y formed on the disk close to the rib w are arranged pintles z forming fulcra for the pivoted valves 2 each having pairs of upstanding lugs 3 penetrated by the pintles and so arranged that when the valve is in the closed position its inner edge 2^1 underlies and may bear flat against the rib w while its outer edge 2^2 overlies and may lie flat against the edge of the disk u at the outer side of the corresponding opening x . In the working stroke of the piston, therefore, the latter will be substantially closed at all points. In the return stroke, inasmuch as the part of each valve at the outer side of its fulcrum is of materially greater area than the part at the inner side thereof, the valve will be turned on its fulcrum until it is stopped by the stem g . In this position it will remain, however, only so long as the pressure of the water passing through the siphon is sufficient to maintain it there, upon which gravity will return it toward the closing position. When the lifting means is fully depressed (as in Fig. 1) it is desirable that the valve should be partly open, so that the shorter leg of the siphon may be duly supplied with the water necessary to start the siphon. I therefore provide the stops or detents 4 which are engaged by the undersides of the valves and tilt them slightly as the disk u approaches its downward limit of movement, such stops or detents being angular pins in the present case projecting in-

wardly from the cylindrical wall of the leg c .

The tube f limits the upward movement of the lifting means, it being abutted by the disk u at the end of the lifting stroke.

Any suitable inlet means, such as the nipple 5 having a valve 6 controlled by a float carrying lever 7 all of well-known construction, may be employed.

In apparatus of this character it is important to prevent as far as possible the admission of air into the siphon during the siphoning action, and especially during the first part thereof. In the present case, by therefore extending downwardly the part of the cap d' through which the stem g passes an appreciable distance as a tube, f , air is prevented from entering the siphon where it is penetrated by the stem until the siphoning action is well under way, the tube f forming in the meanwhile a perfect water-seal and making it unnecessary to provide packing around the stem.

It will be understood that in the present instance the weight of the lifting means, lever p and the short arm n^2 of lever n sufficiently preponderates over the weight of the long arm n' of said lever n always to return the parts to the position shown in Fig. 1 after each working stroke of the lifting means.

Having thus fully described my invention, what I claim as new and desire to secure by Letters Patent is:—

The herein described mechanism for actuating the siphon-starting means of a flushing apparatus including, in combination, a vertical supporting wall, a pair of levers arranged parallel with and close to one vertical surface of said wall and side by side, close to each other, and a bracket secured to said wall and affording a fulcrum support for the levers, one lever being fulcrumed at one end and projecting downwardly at an incline and being adapted to be connected with said starting means at its other end, and the other lever having a short arm projecting substantially horizontally in one direction from the fulcrum of said other lever and coupled with the fulcrum portion of the first lever and also having an angular power-applying arm projecting from the fulcrum of said other lever first upwardly and then in a direction relatively opposite to that in which the short arm projects, substantially as described.

In testimony whereof I affix my signature in presence of two witnesses.

JOHN DENTON.
